UNITED STATES PATENT OFFICE.

CHARLES F. SWELLIE, OF MITTINEAGUE, MASSACHUSETTS.

LIFTING-JACK.

SPECIFICATION forming part of Letters Patent No. 393,527, dated November 27, 1888.

Application filed February 2, 1888. Serial No. 262,813. (No model.)

To all whom it may concern:

Be it known that I, CHARLES F. SWELLIE, of Mittineague, in the county of Hampden and Commonwealth of Massachusetts, have invented a new and useful Improvement in Lifting-Jacks, of which the following is a specification, reference being had to the accompanying drawings, forming part thereof.

The object of my invention is to provide a simple and inexpensive device by means of which a four-wheeled vehicle can be quickly and easily elevated to and retained in a position in which each of its four wheels will be free from the ground, and which device when not in use can be compactly folded together to economize space in storage.

To these ends my invention consists in the lifting-jack hereinafter fully described, and particularly pointed out in the claims.

Referring to the drawings, in which like letters designate like parts in the several figures, Figure 1 is a view in side elevation of a vehicle supported in an elevated position by a lifting-jack constructed according to my invention. Fig. 2 is a perspective view of the lifting-jack as folded together when not in use. Fig. 3 is a similar view of a slightly-modified form of the invention.

The letters A A designate two bars formed into handles at one end, which bars will be of sufficient length relatively to the class of vehicles with which the jack is designed to be used to extend beneath both axles of the vehicle and beyond the end of the same, as shown in Fig. 1. Said bars are securely connected together near each end by cross-bars B B', and upon each of said cross-bars are pivoted two standards, C C, each pair of standards being connected together near their lower ends by braces D D. A third brace, E, is pivotally connected at each end to one of said braces D. By such construction the standards, while being firmly braced in each direction, are adapted to be folded between bars A, as shown in Fig. 2, the brace E preferably having a recess in its upper surface to receive cross-bar B' when the parts are in such position to enable the standards to lie nearly parallel with bars A. When thus folded, the jack is adapted 50 to be suspended upon hooks or nails in the

wall of a stable, for example, or to be otherwise disposed within a very small space.

It is essential, of course, that the jack be provided with means whereby a vehicle after being elevated thereby can be retained in such elevated position, and in Fig. 1 I have shown as such means a chain, F, secured at one end to brace E and at its opposite end to cross-bar B', whereby the swinging movement of the standards upon the cross-bars is stopped 60 slightly beyond a plane perpendicular to bars A. In Fig. 3 I have shown as such means stops a, secured to the inner sides of bars A in position to limit the movement of the standards, as just described. 65

To operate the lifting-jack thus constructed, the bars A are grasped by means of their handles and thrust beneath the vehicle, with the standards resting upon the ground, as shown by broken lines in Fig. 1. The operator then 70 places his foot upon the brace D nearest him and draws the bars A toward him until such movement is stopped by the chain, when the parts will be in the position shown by full lines in Fig. 1. Such movement of the bars A 75 will elevate the vehicle more or less, according to the length of the standards, and the weight of the vehicle will retain the jack in such position until the former is moved in a direction opposite to the movement of the bars, 80 as just described, a sufficient distance to carry the standards past the perpendicular, whereupon the jack folds itself together and the vehicle is returned to the ground. The extended leverage afforded by the standards relatively 85 to bars A renders the operation of elevating a vehicle of moderate weight—such as a carriage or light wagon—very easy for one person, and the elevation of the entire vehicle at one operation enables the wheels to be quickly removed and replaced for any purpose, or to be 90 freely revolved to facilitate washing them.

Wherever it may be desirable—as, for instance, upon the washing-floor of large stables—the standards can be pivotally secured to such 95 floor, and the bars A provided with stops upon their upper surface, as indicated by broken lines in Fig. 3, to be brought into contact with one of the axles of the vehicle as the latter is moved over said bars, whereby by a slight 100

continuation of the movement of the vehicle the jack will automatically elevate it above the floor, whether the vehicle be a light or heavy one.

5 The lifting-jack herein described is simple in construction, can be manufactured cheaply, and is perfect in its operation.

I am aware that lifting-jacks have been heretofore devised by means of which a vehicle can 10 be elevated from the ground in such manner as to clear the four wheels thereof from the ground simultaneously; but such previous implements have been more or less complicated in construction and have, so far as I am aware, 15 employed positive locking devices to retain the jack in its elevated position, which must be disengaged manually before the vehicle can be lowered to the ground. As hereinbefore stated, in the use of the lifting-jack herein 20 shown and described a forward movement imparted to the vehicle itself will cause the jack to lower it to the ground, thus rendering it wholly unnecessary to touch any portion of the jack after the vehicle is once elevated 25 thereon. This feature of my invention is of especial importance when the standards are secured at their lower ends, by pivots or hinges, to the washing-floor of a stable, and the bars A are provided with the stops shown 30 by broken lines in Fig. 3, as just described, inasmuch as both the elevation and lowering of the vehicle can be performed without touch-

ing the jack, and a great saving in time and labor in the use of the jack is effected.

Having thus fully described my invention, 35 what I claim, and desire to secure by Letters Patent, is—

1. The lifting-jack herein described, composed of bars A A, cross-bars B B', standards C, pivotally connected at their upper ends to 40 said cross-bars, braces D D and E, connecting said standards with each other, and a stop for limiting the movement of each of said standards in one direction at a point slightly to one side of a line perpendicular to bars A A, arranged and operating substantially as set forth. 45

2. The lifting-jack herein described, consisting of bars A A, cross-bars B B', standards C, pivoted at their upper ends upon said cross-bars, braces D D, uniting each pair of 50 standards near their lower ends, brace E, uniting said braces D D, and chain F, secured at one end to brace E and at its opposite end to one of the cross-bars, said chain being of such length as to stop the movement of standards C 55 relatively to bars A A in one direction when said standards are slightly to one side of a line perpendicular to said bars, arranged and operating substantially as and for the purpose set forth.

CHARLES F. SWELLIE.
